UNITED STATES PATENT OFFICE.

EDWIN G. FORBES, OF NEW YORK, N. Y.

DESIGN FOR A COMBINED ASH TRAY AND PIPE HOLDER.

Application filed September 24, 1926. Serial No. 19,160. Term of patent 14 years.

To all whom it may concern:

Be it known that I, EDWIN G. FORBES, a citizen of the United States, and a resident of the city of New York, borough of Manhattan, in the county and State of New York, United States of America, have invented a new, original, and ornamental Design for a Combined Ash Tray and Pipe Holder, of which the following is a specification, reference being had to the accompanying drawing, forming part thereof.

In the drawing:

Figure 1 is a plan view of the combined ash tray and pipe holder showing my new design.

Figure 2 is a side elevation thereof.

I claim:

The ornamental design for a combined ash tray and pipe holder, substantially as shown.

EDWIN G. FORBES.
